UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

WEATHER-STRIP.

1,157,125.

Specification of Letters Patent. Patented Oct. 19, 1915.

Application filed March 12, 1913. Serial No. 753,759.

To all whom it may concern:

Be it known that I, HARRY H. SCHROYER, a citizen of the United States, and a resident of the city of Chicago, in the county of Cook and State of Illinois, have invented certain new and useful Improvements in Weather-Strips; and I do hereby declare that the following is a full, clear, and exact description of the same, reference being had to the accompanying drawings, and to the numbers of reference marked thereon, which form a part of this specification.

This invention relates to new and useful improvements in weather strips adaptable to general use, but it is shown more particularly embodied in a weather strip or guard for car windows.

It is an object of this invention to provide sealing means between the sliding stiles of a window sash and the frame therefor, the sealing of which is augmented by wind pressure.

It is also an object of this invention to provide an interfitting weather stripping device whereby a portion of the window framing affords an element of the weather stripping for one or more windows.

It is also an object of this invention to provide a weather stripping means which will afford a guide and retaining means for the sliding window sash.

It is furthermore an object of this invention to provide weather stripping means between the sliding stiles of a window sash and the frame therefor, which serves as a guide and retaining means for the sash, and is impervious to weather conditions.

It is finally an important object of this invention to provide a simple, durable and inexpensive weather strip adapted to effectually seal the window.

The invention (in a preferred form) consists in the matters hereinafter described and more fully pointed out and defined in the appended claims.

In the drawings: Figure 1 is a fragmentary exterior view of a car window equipped with a device embodying the principles of my invention. Fig. 2 is a section on line 2-2 of Fig. 1. Fig. 3 is a transverse vertical section on line 3-3 of Fig. 1. Fig. 4 is an enlarged sectional detail of the resilient means bearing on the inner sash to prevent rattling of the same. Fig. 5 is a section on line 5-5 of Fig. 4, showing the resilient means in

elevation. Fig. 6 is a section on line 6-6 of Fig. 4. Fig. 7 is an enlarged fragmentary sectional detail illustrating the relation of the weather stripping elements.

As shown in the drawings: The outer sliding sash of a car window is designated by the reference numeral 1, said sash comprising a bottom rail 2, and stiles 3, and, together with an inner sash 4, is slidably mounted in the window frame. As shown, 60 said inner sash is adapted to slide between inner and outer stops 5 and 6, respectively, comprising strips of resilient metal which are suitably engaged in window posts of a car frame. As shown in Fig. 3, each of 65 said inner and outer sashes closes downwardly upon an inclined outer sill 7, which has connected therewith, as is usual, an inner sill 8, on the interior of the car.

Secured on the outside and forming a 75 part of the car window posts are cheek plates 9, which are, as shown, channeled sections and provided at their edges with laterally extended flanges 10.

The stiles 3, of the outer sash are provided 80 in their outer faces for their whole length each with a longitudinally extending stepped recess or rabbet, in which is rigidly secured a small T bar 11, with the outer face thereof 85 flush with the outer face of the stile member. As shown, one flange of said T member fits closely in one of the stepped recesses of the stile, and the other flange projects partially over the other stepped recess in said stile, thereby affording a 90 groove to receive the flange 10, of the cheek plate. As shown in Figs. 1 and 2, said outer cheek plate 9, extends over and around each of the window posts to afford the engaging flanges 10, for one side of the adjacent outer 95 window sashes.

Means are provided within the stops 6, to retain the inner sash 4, closely against the inner stop 5. Such means comprises an angled resilient bar 12, spot welded on the inner side of the stops 6, at one of its extremities, and with the outer end stamped outwardly into a cup member 13, projecting through an aperture in the stop 6. An integral tongue of metal 14, is bent inwardly 100 on each side of said cup member and said tongue slidably engages within a spiral spring 15, which bears at one of its ends against said cup member 13, and at the other 105 against the opposite wall of the stop 6. Thus 110

- it is seen that the cup member 13, is pressed outwardly against the stiles of the inner sash due to the resiliency of the angled bar 12, and also the spiral spring 15.
5. The operation is as follows: Inasmuch as the stops 5 and 6, are resiliently engaged in the window posts of the car and are readily detachable therefrom, the outer recessed sash 1, without the T bars 11, is placed in position from the interior of the car, and the T bars 11 are then secured to the sash from the outside, thereby inclosing the flanges 10, within the grooves so formed to retain the sash in place. The outer stops 6, are next 10 placed in position in the window posts and the sash 4 mounted from the interior of the car, after which the inner stops 5, are sprung into place. It will be readily seen from the drawings that the outer sash is 15 allowed a certain amount of transverse movement or play between the stop 6, and the weather strip flange 10. This is for the purpose of permitting the extended flange of the T bar 11, to be forced tightly against 20 the flange 10, due to wind pressure when the car is in motion, thereby affording an automatically acting weather strip in which the sealing effect is augmented by the tendency of the air to force its way inwardly between the sash and the frame. Of course, 25 where the window posts, as shown in Figs. 1 and 2, happen to be of slightly different construction, it is only necessary to remove the inner and outer stops 5 and 6, respectively 30 from the narrow posts, inasmuch as the grooves therein for the reception of said stops will permit manipulation of the sashes around the stops 5, and 6, of the wider posts for the positioning of the sashes.
- 35 40 I am aware that details of the construction are open to wide variation without departing from the principles of my invention, and I therefore do not purpose limiting the patent granted otherwise than necessitated by the prior art.

I claim as my invention:

1. In a car window construction, a window post, a sliding window sash, a cheek plate secured on the window post, a flange

on said cheek plate engaging the outer face 50 of said sash, and a bar on said sash overlying said flange.

2. In a car window construction, the combination with the sliding sashes of adjacent windows, of a cheek plate secured on the 55 window post between said windows, flanges on said cheek plate engaging the outer faces of the adjacent window sashes to afford a seal therefor, and bars on said sashes overlying said flanges.

3. In a device of the class described, the combination with the grooved sliding sashes of adjacent windows, of cheek plates secured on the window posts between said windows, flanges on each of said cheek plates engaging in the grooves of adjacent window sashes to afford a seal therefor, and bars on said sashes overlying said flanges.

4. In a car window construction, a series of sliding grooved sashes, an integral flange member between each of said sashes affording means engaging in the grooves of adjacent sashes to afford a guide and sealing means therefor, and bars on said sashes overlying said flanges.

5. In a car window construction, a window post, a channeled member extending around the exterior thereof, a grooved sliding sash on each side of said window post, flanges on said channeled member adapted 75 to engage in the said grooves to afford a guide and seal therefor, and bars on said sashes overlying said flanges.

6. In a car window construction, a window post, a sliding window sash having a 85 stepped recess in the stile thereof, a T bar rigidly engaged therein affording a groove, a cheek plate on said window post, and a flange thereon adapted to engage in said groove to afford retaining and sealing means 90 for said sash.

In testimony whereof I have hereunto subscribed my name in the presence of two subscribing witnesses.

HARRY H. SCHROYER.
